UNITED STATES PATENT OFFICE

2,062,036

CALENDAR CALCULATING DEVICE

Neal F. Mears, Chicago, Ill.

Application April 19, 1935, Serial No. 17,288

12 Claims. (Cl. 40—115)

My invention relates to an improved calendar calculator which is particularly useful in the chronological field for determining the dates of the month and the days of the week of certain past or future events.

Among the important objects of my invention are: to provide a simple, inexpensive device for calculating dates; to provide a device to find any desired year without recourse to tables, calculations or inter-referenced data; to provide a device which will give all the months of any desired year at one setting; to provide a device which shows the periodic agreement existing between the calendars of different years; to provide a device which will enable the ordinary person to determine desired days and dates as easily in the discarded old style calendar as in the current new style calendar; to provide a device which permits the use of data beyond the scope of ordinary problems and which hence supplies information beyond the limits of ordinary need; and in general to provide an improved and simplified structure which will illustrate these and many other calculations and reorganizations of chronology.

My improved device is disclosed on the accompanying drawing in which

Fig. 1 is a plan view of the device with a part of the upper member broken away on the one side, and a part of both the upper and intermediate members broken away on the other side.

Fig. 2 is a horizontal diametral sectional view.

The structure shown comprises three members, a large or base disc, an upper or smaller disc, and an intermediate disc. These members are connected to be adapted for relative parallel movement either in straight lines or along curved lines. In the device shown the members are circular and are pivoted together at their centers to adapt them for relative rotational movement.

The large or base disc 10 has outer and inner rows 11 and 12, respectively, printed thereon, these rows being circular and concentric. In the outer row 11 are the numerals from one to ninety-nine, two sets of double ciphers, and one figure two thousand, arranged in a certain predetermined calculated succession and subdivided into sections. In the inner row 12 are day figures arranged in fourteen conventional months (each consisting of thirty-one days), placed so that the two which begin on the same day of the week are adjacent. Both these rows, 11 and 12, are arranged to read in clockwise order.

The intermediate disc 13 has a series of seven windows 14, 14, adapted to register with the in-

ner row 12 on the large disc and to disclose alternate month sections of said row 12. In segments alternating with these windows 14, 14, are century indicia 15, 15. Outside one of these century sections and on the periphery of the intermediate disc is the year indicator 16, which is adapted to register with a chosen section of the outer row 11 of the large disc.

The small disc 17 has seven windows, 19, 19, adapted to register and coincide with the windows, 14, 14, on the intermediate disc 13.

Outside the windows 19, 19, are month names 18, 18, arranged in a predetermined calculated order. For convenience, all these month names are followed by figures indicating the number of days in each month. There are two rows of such month names, arranged concentrically, and those month names includable in a leap year calculation are enclosed by a border.

The small disc 17 also has another window 20, 20 identified by the word "century" 21, and this window is positioned to register with the century indicia 15, 15, on the intermediate disc 13.

The three members, the large disc 10, the intermediate disc 13, and the small disc 17 are pivoted concentrically as by means of the eyelet e.

The theoretical basis underlying the construction of the illustrated form of this calendar calculating device is that each month of the year begins on some day of the week, and that, in every year, each day of the week will occur one or more times as the first day of a month. On this premise there are only seven different months in a year, according to the day of the week on which each begins. Since leap year somewhat changes the succession of days, two groups of seven different months, each month therein beginning on a different day of the week, with due allowance for leap year, will include all possible months. The seven windows 19, 19, of the large member 10, which coincide with the seven windows 14, 14, of the intermediate member 13, thus show all the months of the year in the seven which they disclose. It is obvious that this grouping of day figures 12, 12, and the operation thereon of the selective windows 14, 14, and 19, 19, produce, in effect, a series of fourteen different years—seven years being regular years and each beginning on a different day of the week— and seven being leap years and each beginning on a different day of the week. Thus there is a regular year wherein Monday is the first day of the year, a leap year wherein Monday is the first day of the year, and so on, for each day of the week.

The various possible forms of my device will, therefore, select one of these fourteen years, however the day figures and month names may be grouped, according to the century and the 5 year figures combined.

The operation of my improved calendar calculating device can now be readily understood. Suppose it is desired to find the calendar for the year 1935. The procedure is illustrated in Fig. 1. 10 The small member 17 is rotated until the indicia "New style—1500, 1900, 2300," appear in window 20 which has associated with it the selective indicator "Century" 21. This action, by selecting the century "1900" has set the device for the 15 first two figures (i. e. 19—) of the year 1935, New style. The small member 17 and the intermediate member 13 are now held together and rotated as one until the selective indicator "Year" 16 on the intermediate member 13 registers with the group of figures, in row 11 on the large member 10, which contains the numeral "35". This last action has set the device for the 20 last two figures (i. e.—35) of the year 1935. It will now be noticed that certain day figures 12, 25 12, appear through the windows 14, 14, and 19, 19, and that the names of the months 18, 18, agree with the figures in the months 12, 12, so that an accurate calendar for the year 1935 is now shown.

30 The proper century figures and the proper year figures are indicated in the drawing of this device so that there may be selected any year from 8 B. C., the first consistent year of our present calendar system, to 2399 A. D.—but this 35 scope is determined by the century indicia 15, 15, on member 13, and extensions may obviously be made by properly amending the century indicia.

A great many other chronological problems can be worked out on my improved device. Its 40 operation is very simple. There are only three adjustable members and after they are associated by the process of two settings the desired information is clearly visible and definite.

I do not, of course, desire to be limited to the 45 exact construction, arrangement and operation shown and described, as changes and modifications might readily be made which would still come within the scope of my invention.

I claim as new and desire to secure by Letters 50 Patent:

1. A calendar calculating device comprising the combination of a large member bearing year figures and day figures; an intermediate member bearing century figures and having a year 55 figure selector which operates on the year figures on the large member, and having seven windows which register with the day figures on the large member; and a small member bearing month names and having seven windows which register 60 with the windows of the intermediate member, and having a century selector window which registers with the century figures on the intermediate member; the three members being pivoted together for concentric rotation.

65 2. A calendar calculating device comprising the combination of one member bearing year figures and day figures; another member bearing century figures and having means for selecting the year figures on the first mentioned member; another member bearing month names and having 70 means for selecting the century figures on the second mentioned member, and means for selecting the day figures on the first mentioned member; all members being adapted for relative movement.

3. A calendar calculating device comprising a plurality of members, one of said members bearing day figures and year figures; another of said members bearing century figures and having a selector adapted to operate on the year figures on the first mentioned member; another member bearing month names and having a selector adapted to operate on the century figures on the second mentioned member and also having seven selectors which operate on the day figures on the first mentioned member and resolve the twelve months of any year into seven months. 5

4. A calendar calculating device comprising one member sliding over another and selecting the months of a year; another member sliding 15 over a member and selecting the hundreds figures of a year; another member sliding over a member and selecting the tens figures of a year; the whole being adapted for relative movement and setting to give the year and the proper 20 months associated with it.

5. A calendar calculating device comprising a plurality of members, one member having thereon year figures and day figures; another member having thereon century figures; another member having thereon month names; the second and third mentioned members having associated therewith selecting means; and all members being relatively movable so that the center lines 25 of the pathways of the indicia on all members 30 remain equidistant while said members are in motion being set.

6. A calendar calculating device comprising a plurality of members, one member having thereon day figures; another member having thereon month names; another member having thereon century figures; the indicia on each of said members interacting with century figures and year figures so that setting of said members can be made to give a desired year and the proper 40 months associated therewith.

7. A calendar calculating device comprising a plurality of members, one member having thereon day figures; another member having thereon month names; another member having thereon century figures; the indicia on each of said members interacting with century figures and year figures so that a setting of said members can be made to give a desired year and to show all of the months of said year at once. 50

8. A calendar calculating device comprising a plurality of members, one member having day figures and year figures; another member having century figures and a selector which operates on one portion of the indicia on the first mentioned 55 member; another member having month names and a selector which operates on the indicia on the second mentioned member; a setting allowing an association of another portion of the indicia on the first mentioned member and the indicia 60 on the third mentioned member.

9. A calendar calculating device having a plurality of members bearing day figures, year figures and century figures, and month names; and associated therewith selectors for months, year 65 and century; the whole so adapted for movement that when the total figures comprising a desired year are set adjacent, the proper calendar months for that year will be selected.

10. A calendar calculating device having a plurality of members bearing day figures, year figures and century figures, and month names, and associated therewith selectors for months, year and century, the whole so adapted for movement that when the total figures comprising a desired 70 75

year are set adjacent all except the proper calendar months for that year will be excluded from view.

11. A calendar calculating device having relatively movable members, the indicia on one member adapted to conjoin with the indicia on a second member, the indicia on a second member adapted to conjoin with the indicia on a third member, and the indicia on a third member adapted to conjoin with the indicia on the first member, the whole structure being adapted so that when an indicator on the first mentioned member is set to century figures on the second mentioned member, and an indicator on the second mentioned member is set to year figures on the third mentioned member, the month names

on the first mentioned member will conjoin with proper day figures on the third mentioned member, and the whole calendar of the selected year will then be shown.

12. A calendar calculating device having a top member with an indicator which selects indicia on a middle member, a middle member having an indicator which selects indicia on a bottom member, and a bottom member with indicia which then conjoin with indicia on the top member, the whole structure being adapted so that when the indicator settings are made the indicia on the top member and on the bottom member conjoin to give the proper months and days of the selected year.
